UNITED STATES PATENT OFFICE.

HARRY B. WHITE, OF CANTON, OHIO, ASSIGNOR TO THE HOOVER COMPANY, A CORPORATION OF OHIO.

SUCTION SWEEPER.

Application filed July 12, 1923. Serial No. 650,982.

This invention relates to suction cleaners of the ordinary portable type wherein there is provided a movable casing having a motor, a pumping device and an inlet mouth, 5 the whole being moved about over the surface to be cleaned by means of a pivotally mounted handle, the air displaced by the pumping device and the dirt gathered by the cleaner being delivered into a porous bag, one end of which is secured to the casing and the other end to the pivoted handle.

It has heretofore been customary to attach the upper end of this bag to the handle by means of an elastic member or by a slider bar, as shown in the patent to Howard Earl Hoover, No. 1,264,073, so as to maintain the bag taut at all times without impeding the movement of the handle and also to permit the shortening of the bag which occurs upon 20 inflation.

Due to the fact that the pivotal points of the handle and the dust bag are separated, the connection between them must be flexible in order that the handle may be moved 25 through a vertical plane about its pivot point without placing an undue strain upon the bag.

The objects of the present invention are the provision of a neat compact and self-contained suspending device for this apparatus; the provision of a flexible connection between the handle and the dust bag, such that the latter may not be over-strained and torn.

Other objects and advantages will be apparent as the description proceeds.

In the drawing accompanying and forming a part of this application wherein I have illustrated one embodiment of my said 40 invention,

Figure 1 represents a side elevation of a complete cleaner embodying my invention, minor details being omitted.

Figure 2 represents a rear elevation of a 45 complete cleaner, details of the cleaner being omitted.

Figure 3 is an elevation of the suspending device,

Figure 4 is an elevation of one of the arms 50 of the suspending device,

Figure 5 is an end view of one of the arms of the suspending device.

Like parts are indicated by the same ref-

erence numerals in all figures. The ordinary vacuum cleaner comprising a fan 55 chamber, a fan, a motor for driving the fan, and a suction mouth and discharge all mounted on rollers so that the machine may be propelled over the surface to be cleaned is indicated as a whole by numeral 10. Attached to the cleaner is a pivoted handle 11 by means of which the machine may be propelled and connected to the discharge is a porous dust-bag 12 ordinarily formed of a more or less porous fabric.

Since the pivot points of the handle 11 and bag 12, respectively, are separated, any connection between them must be of a flexible nature and one which will readily give on changing of position of the handle. This connection as embodied in my invention comprises two members 13—13 pivotally mounted at a point intermediate their ends, such as at 14. At the point of pivotal connection of levers 13 there is provided a pin 15 on 75 which these levers are pivoted and there is provided a torsion spring member 16 surrounding and supported by this pin 15, the ends of the spring being relatively straight and extending one in each direction from 80 the pivot point and contacting with the under-side of levers 13. The outer ends of levers 13 are provided with means such as shown at 17 to which the bag may be attached. The inner ends of the lever are provided with means such as 18, whereby the member connecting this lever system to the handle 11 may be attached. This connecting member indicated in its entirety as 19 comprises at its lower end a double looped member, such as is designated as 20. This supporting member may be made of wire, fabric or any flexible material such that the lower loops 20 may approach in close proximity to one another when such position becomes necessary due to movement of the inner ends of the members 13 to which these loops are attached.

The upper loop 21 of this suspension member is secured to the cleaner handle 11 by means of a hook-like member 22 100 which is securely fastened to the handle. As shown in the drawings, the outer ends of members 13 are secured to the dust-bag 12 by means of hooks 23 which are secured to the upper edges of the bag. These hooks 105 23 pass through openings 17 in the outer

ends of members 13, whereby the levers 13 are securely fastened to the upper end of the dust bag.

This suspension means operates in the following manner. When the handle is down in the ordinary operating position, the torsion spring 16 causes the levers 13 to assume a position substantially in a straight line and suspension member 19 holds the upper end 10 of the bag up close under the handle. When the handle is moved upwardly to a substantially vertical position, extra length necessary so that undue strain will not be exerted on the bag is provided by the spring 15 16 giving so that the arms 13 assume positions more or less in the form of an inverted V, thus providing the extra length necessary. This arrangement always maintains the upper end of the bag 12 close to the handle in a neat and trim manner and permits the necessary lengthening of the bag supporting member upon movement of the handle.

This suspension member provides a convenient means whereby the upper end of the dust bag may be held and shaken when it is desired to remove the dirt which has collected therein. Furthermore, the double side support of the bag provides a flat suspension and a greater clearance between the bag 30 and the floor when the bag is deflated.

It will be understood that many changes in the construction may be made within the

scope of the appended claims without departing from the spirit and scope of my invention.

I claim:—

1. In combination with a suction sweeper having a pivoted handle and a dust bag, means for suspending the dust bag from the handle comprising levers adapted for pivotal mounting intermediate their ends, a member on which the levers pivot, a spring supported by the member and tending to maintain said levers in alignment, one end of the levers being provided with means whereby the bag may be attached, the other end of the levers provided with means whereby the suspension member is attached to the pivoted handle.

2. In a suction sweeper provided with a pivoted handle and a dust collector, an extensible connecting means between the handle and the dust collector comprising levers adapted for pivotal mounting, means on which the levers are pivoted, one end of the levers adapted for attachment to one of and their other ends adapted for attachment to another of the connected members in combination with means tending to cause separation of the ends of said levers.

Signed at North Canton, in the county of Stark and State of Ohio, this 25 day of April 1923.

HARRY B. WHITE.
